UNITED STATES PATENT OFFICE.

CHRISTOPHER SWITZER AND FREDRECK SUNDMAN, OF DOE RUN,
MISSOURI.

COMBINED RAILWAY CATTLE-GUARD AND METALLIC CROSS-TIE.

No. 853,135.

Specification of Letters Patent.

Patented May 7, 1907.

Application filed February 28, 1907. Serial No. 359,802.

To all whom it may concern:

Be it known that we, CHRISTOPHER SWITZER and FREDRECK SUNDMAN, citizens of the United States, residing at Doe Run, in the county of St. Francois and State of Missouri, have invented a new and useful Combined Railway Cattle-Guard and Metallic Cross-Tie, of which the following is a specification.

The invention relates to a combined railway cattle guard and metallic cross tie.

The object of the present invention is to provide a simple and comparatively inexpensive combined railway cattle guard and metallic cross tie, adapted to strengthen a track and capable of effectually preventing cattle from crossing it.

A further object of the invention is to provide a combined railway cattle guard and metallic cross tie, having cattle guard members, arranged to brace the rails at the outer sides thereof, whereby the rails are effectually prevented from spreading.

The invention also has for its object to provide a combined cattle guard and cross tie, adapted to afford passage-ways or conduits for water to permit the same to flow readily across the track without impairing the same.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a plan view of a combined railway cattle guard and metallic cross tie, constructed in accordance with this invention. Fig. 2 is an enlarged longitudinal sectional view, taken substantially on the line $x-x$ of Fig. 1. Fig. 3 is a transverse sectional view, taken substantially on the line $y-y$ of Fig. 2. Fig. 4 is a perspective view of one of the cattle guard members. Fig. 5 is a reverse plan view of the top plate of the cross tie, illustrating the arrangement of the clamp-engaging keys and the double wedge for spreading the inner ends of the keys. Fig. 6 is a detail view of one of the keys. Fig. 7 is a detail perspec-

tive view of one of the clamps. Fig. 8 is a reverse plan view of the same and a portion 55 of one of the cattle guard sections. Fig. 9 is a detail sectional view of a portion of the cross tie, illustrating the manner of securing the top plate to the sides.

Like numerals of reference designate corresponding parts in all the figures of the drawings.

1 designates a hollow metallic cross tie, forming a conduit to permit water to flow across the track without impairing the road 60 bed, and consisting of a horizontal bottom and upwardly converging inclined sides 2, formed integral with the horizontal bottom, as clearly illustrated in Fig. 3 of the drawings.

The metallic cross tie is provided with a removable horizontal plate 3, detachably secured to the sides 2 by screws 4 and arranged on and supported by the upper edges of the said sides 2. The screws 4, which may be of 70 any desired number, pierce the top plate and engage threaded sockets of the sides 2 of the cross tie.

The top plate presents a flat upper face to receive rails 5, and it is provided at the sides 80 of the bottom flanges of the rails with slots 6, arranged in pairs and spaced apart. The slots receive depending shanks 7 of clamps 8, which engage the bottom flanges of the rails and which also interlock with and engage intermediate and outer cattle guard members 9 and 10, whereby the latter are securely fastened on the upper faces of the cross ties. The slots are disposed transversely of the cross ties and the shanks 7, 85 90 which depend below the lower face of the top plate of the cross tie, are provided with registering openings 11, through which pass longitudinal keys 12, whereby the clamps are detachably retained in engagement with the rails and with the cattle guard members. The keys 12 are provided at their outer ends with hook-shaped heads 13, and are adapted to be engaged by a suitable tool for enabling them to be readily withdrawn, when it is desired to remove either the cattle guard members or the rails.

The inner ends of the keys are recessed vertically to provide tapering recesses 14, arranged to receive tapered ends 15 of a fixed 100 wedge 16, formed integral with and located

at the lower face of the top plate of the cross tie, and arranged in the path of and adapted to spread the split ends of the keys, whereby the latter are positively retained in engagement with the shanks of the clamps. The inner ends of the keys are maintained in their spread or locked position by the tapered ends of the double wedge, which is in the form of a longitudinal rib or flange, and which is adapted to materially increase the strength of the top plate of the cross tie. In order to facilitate the spreading of the inner ends of the keys, the latter are also split horizontally at 17 at opposite sides of the tapering recesses. 15 The split ends of the keys are spread at the inner shanks, as clearly shown in Fig. 6 of the drawing, whereby the keys are positively locked against outward movement.

Each clamp is provided at the upper end 20 of the shank with a head, extending longitudinally of the cross tie in opposite directions to form a rail-engaging portion and a cattle guard-engaging portion. The rail-engaging portion is provided with a flat inclined lower 25 face 18 to fit and conform to the configuration of the upper face of the bottom flange of the rail, and it has an inner shoulder 19 to engage the edge of the rail. The cattle guard-engaging portion is provided with a curved 30 lower engaging face 20 and is rounded at the outer edge 21.

Each cattle guard member is inverted V-shaped in cross section, and is composed of oppositely inclined sides, formed integral 35 with each other and provided at their lower edges with inwardly extending narrow longitudinal flanges 22, spaced apart at the median line of the bottom of the cattle guard member and presenting flat lower faces to the 40 top plate of the cross tie. The inclined sides of the inverted V-shaped cattle guard sections or members have their outer faces arranged in the same plane as and forming continuations of the inclined sides 2 of the 45 hollow cross tie. The outer sections 10 are provided at the screws 4 with grooves 4^a to afford access to the heads of the screws. The longitudinal flanges 22, which are recessed at their upper faces, present concave faces 23 to 50 the lower curved face 20 of the clamp, and the longitudinal flanges are also cut away to present curved end edges 24 to fit the clamps.

The longitudinal bottom flanges of the cattle guard sections are provided with depending tapering studs 25, which fit in corresponding sockets 26, formed by perforating the top plate 3 of the metallic cross tie adjacent to the sides thereof. The depending 55 tapering studs firmly interlock the cattle guard sections with the metallic cross tie for holding the former against horizontal movement on the latter, and the cattle guard sections are securely maintained in such interlocked relation by the clamps. The depend-

ing studs extend below the lower face of the top plate and engage the inner face of the sides of the cross tie of the upper edges thereof, whereby the top plate is held against horizontal movement in either direction transversely of the cross-tie. This construction is adapted to relieve the screws 4 of strain. 70

The ends of the inner or intermediate cattle guard sections are spaced from the rails, and the inner ends 27 of the outer cattle guard sections extend over the contiguous clamps and fit against the outer sides of the rails to form braces for preventing the rails from spreading, whereby accidents resulting from the spreading of the rails will be reduced to a minimum. As the inner ends of the outer cattle guard sections fit against the heads of the rails and as the clamps firmly engage the bottom flanges of the said rails, it will be apparent that the rails are firmly secured to the metallic cross tie and are effectively prevented from spreading. 80

Having thus fully described our invention, what we claim as new, and desire to secure by Letters Patent, is—

1. In a device of the class described, the combination of a cross tie, rail-engaging means, and cattle guard sections detachably secured to the cross tie by the rail-engaging means.

2. In a device of the class described, the combination of a cross tie, cattle guard sections, and rail-engaging clamps having projecting portions engaging the cattle guard sections and securing the same to the cross tie.

3. In a device of the class described, the combination with a cross tie, and rails, of cattle guard sections arranged on the cross tie, and clamps located at opposite sides of the rails and having oppositely projecting portions engaging the rails and the cattle guard sections for securing the same to the cross tie. 105

4. In a device of the class described, the combination with rails, of cattle guard sections fitting against the outer sides of the rails and constituting braces to prevent the rails from spreading.

5. In a device of the class described, the combination with rails, of cattle guard sections fitting against the outer sides of the rails to prevent the same from spreading, and rail-engaging clamps provided with means for also engaging the cattle guard sections. 115

6. In a device of the class described, the combination with rails, of an intermediate cattle guard section spaced from the inner sides of the rails, an outer cattle guard section fitting against the outer sides of the rails and forming braces to prevent the same from spreading. 125

7. In a device of the class described, the combination with a cross tie, and rails, of cattle guard sections having inclined sides 130

and provided with bottom flanges fitted on the cross tie, and means for securing the rails and the cattle guard sections to the cross tie.

8. In a device of the class described, the combination with a cross tie, and rails, of cattle guard sections provided at the bottom with depending studs engaging the cross tie for holding the sections against horizontal movement, and means for retaining the sections in engagement with the cross tie.

9. In a device of the class described, the combination with rails, and a cross tie, of cattle guard sections provided with spaced bottom flanges having means for engaging the cross tie, and rail-engaging means provided with means for engaging the bottom flanges of the cattle guard sections for retaining the same in engagement with the cross tie.

10. In a device of the class described, the combination with rails, and a cross tie, of cattle guard sections having spaced bottom flanges, and clamps provided with heads having oppositely projecting portions engaging the rails and interlocked with the bottom flanges of the cattle guard sections.

11. In a device of the class described, the combination with rails, of hollow cattle guard sections, and rail-engaging clamps having means projecting into the ends of the hollow cattle guard sections for engaging the same.

12. In a device of the class described, the combination with rails, of cattle guard sections having inclined sides, and spaced bottom flanges cut away at the terminals, and rail-engaging clamps having projecting portions extending into the cattle guard sections and engaging the cut away portions of the bottom flanges.

13. In a device of the class described, the combination with rails, of hollow cattle guard sections cut away at the bottom and beveled at the cut away portions, and rail-engaging clamps having projecting portions extending into the cattle guard sections and conforming to the configuration of and engaging the cut away and beveled portions thereof.

14. In a device of the class described, the combination of a hollow cross tie, cattle guard sections, rail-engaging clamps having projecting portions for engaging the cattle guard sections, said rail-engaging clamps being also provided with depending shanks extending through the top of the cross tie, and keys passing through the shanks.

15. In a device of the class described, the combination of a hollow cross tie, cattle guard sections arranged thereon, rail-engaging clamps provided with means for engaging the cattle guard sections and having depending shanks extending through the top of the cross tie, keys extending through the shanks and having split portions, and means ar-

ranged in the path of the keys for spreading the split ends thereof.

16. In a device of the class described, the combination of a hollow cross tie, cattle guard sections arranged thereon, rail-engaging clamps provided with means for engaging the cattle guard sections and having depending shanks extending through the top of the cross tie, keys extending through the shanks and having split portions, and a fixed wedge arranged in the path of the keys for spreading the split ends of the same.

17. In a device of the class described, the combination of a hollow cross tie, cattle guard sections arranged thereon, rail-engaging clamps provided with means for engaging the cattle guard sections and having depending shanks extending through the top of the cross tie, keys extending through the shanks and having split portions, and an oppositely tapered wedge having its terminals arranged in the path of the keys for spreading the split portions thereof.

18. In a device of the class described, the combination of a hollow cross tie provided at the lower face of its top with an integral wedge tapered at each end, rail-engaging clamps extending through the top of the cross tie, and keys piercing the clamps and having split portions arranged to be spread by the wedge.

19. In a device of the class described, the combination of a hollow cross tie having an interiorly arranged wedge, a rail-engaging clamp extending into the cross tie, and a key piercing the clamp and arranged to be spread by the wedge.

20. In a device of the class described, the combination of a hollow cross tie having an interiorly arranged wedge, a clamp extending into the cross tie, and a key piercing the clamp and provided at its inner end with a tapering recess and split at opposite sides of the same, said recess being adapted to receive the wedge, whereby the split end of the key is spread.

21. A device of the class described comprising a cross tie having inclined side faces, and a cattle guard section detachably fitted on the cross tie and having inclined faces arranged in the same plane as and forming continuations of the inclined faces of the cross tie.

22. A device of the class described comprising a hollow cross tie having inclined faces and forming a conduit for water, and an inverted V-shaped cattle guard fitted on the cross tie and having inclined sides forming continuations of the sides of the cross tie.

23. In a device of the class described, the combination of a hollow cross tie having inclined sides, an inverted V-shaped cattle guard section provided at the lower ends of its sides with spaced bottom flanges fitted on the cross tie, and means for engaging the bot-

- tom flanges of the cattle guard sections for securing the same to the cross tie.
24. In a device of the class described, the combination of a hollow metallic cross tie forming a conduit or passage for water and comprising a bottom, sides, and a top plate secured to the sides, a cattle guard section detachably interlocked with the top plate, and means for securing the cattle guard section in its interlocked relation.
25. In a device of the class described, the combination of a hollow metallic cross tie comprising a bottom, sides, and a top plate provided with sockets, a cattle guard section having depending studs fitting in the sockets of the top plate, and fastening devices retaining the studs in the sockets and securing the cattle guard section to the top plate.
26. A hollow cattle guard section having spaced sides and inclined flanges.
27. A hollow cattle guard section having spaced sides and inclined flanges, said flanges having depending pointed studs.
28. In a device of the class described, the combination of a hollow cross tie, cattle guard sections, rail-engaging clamps having projecting portions for engaging the cattle guard sections, said rail-engaging clamps serving as connecting means between the cattle guard sections and the tie.
29. In a device of the class described, the combination with cross ties, and rails, of cattle guard sections, and rail-engaging clamps for connecting the adjacent ends of the cattle guard sections and the bottom flanges of the rails, and also for connecting the sections to the cross ties.
30. In a device of the class described, the combination of a hollow cross tie, cattle guard sections arranged thereon, rail-engaging clamps provided with means for engaging the cattle guard sections and having depending shanks extending through the top of the cross tie, and means for connecting the shanks to the cross tie so as to lock the rails, cattle guard sections and the cross tie together.
31. In a device of the class described, the combination of a hollow cross tie composed of a bottom, sides, and a top plate, and a cattle guard section provided with studs piercing the top plate of the cross tie and engaging the sides thereof.
32. In a device of the class described, the combination of a hollow cross tie composed of a bottom, sides, and a top plate, and a cattle guard section provided at opposite sides with depending studs piercing the top plate and projecting below the same and engaging the inner face of each side of the cross tie.

In testimony that we claim the foregoing as our own, we have hereto affixed our signatures in the presence of two witnesses.
